Primary Examiner — Michelle E. Wilson

Assistant Examiner — Clese Moore, Jr.

(57) CLAIM

The ornamental design for baby footed pajamas, substantially as shown and described.

DESCRIPTION

FIG. 1 is a top, front and left side perspective view of baby footed pajamas, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate the portions of the baby footed pajamas, which form no part of the claimed design.

1 Claim, 7 Drawing Sheets(56)
